US00D534121S

(12) **United States Design Patent** (10) **Patent No.:** **US D534,121 S**
(45) **Date of Patent:** **** Dec. 26, 2006**

(54) **VIBRATION MOTOR**

(75) Inventors: **Kazuo Morita**, Tokyo (JP); **Hidehiro Uchiumi**, Tokyo (JP)

(73) Assignee: **Namiki Precision Jewel Co. Ltd.**,
Tokyo (JP)

(**) Term: **14 Years**

(21) Appl. No.: **29/223,900**

(22) Filed: **Feb. 22, 2005**

(30) **Foreign Application Priority Data**

Aug. 26, 2004 (JP) 2004-025646

(51) **LOC (8) CI.** **13-01**

(52) **U.S. Cl.** **D13/112**

(58) **Field of Classification Search** D13/112,
D13/113, 114, 199; 310/15, 81, 89; 340/388.1,
340/407.1; 381/191

See application file for complete search history.
